United States Patent Office

Des. 226,393
Patented Feb. 27, 1973

226,393

SERVING TRAY

Benjamin Greenstein, Forest Hills, N.Y., assignor to
Daher Company, Inc., Long Island City, N.Y.

Filed Mar. 12, 1971, Ser. No. 123,926

Term of patent 14 years

Int. Cl. D7—99

U.S. Cl. D44—10 E

FIG.1.

FIG.2.

FIG.3.

FIG.4.

FIG. 1 is a top perspective view of a serving tray, showing my new design,

FIG. 2 is a top plan view,

FIG. 3 is a side elevational view, and

FIG. 4 is an end elevational view thereof.

The bottom of the design is substantially plain and unornamented.

I claim:

The ornamental design for a serving tray, substantially as shown and described.
